TENON GROOVING MACHINE

Filed July 17, 1925

2 Sheets-Sheet 2

Fig. 2.

UNITED STATES PATENT OFFICE.

FRED J. MURDOCK, OF STATESVILLE, NORTH CAROLINA.

TENON-GROOVING MACHINE.

Application filed July 17, 1925. Serial No. 44,196.

In various localities, the manufacture of what are known as old time home-made chairs has reached the stage of a substantial industry. Such chairs are made from timber while green, and the rungs are provided with tenons which are circularly grooved or recessed after the rungs have thoroughly dried, while the bores or cavities in the posts, legs or similar parts to receive 10 the tenons are made while the timber is green and of sizes much smaller than the tenons requiring the tenons to be driven in. When the parts having the bores or cavities thoroughly dry, the bores or cavities draw 15 securely about the tenons and prevent separation of the parts, thereby rendering the construction of the chair more durable.

Hence, it is a purpose of this invention to provide an improved cutter head of double 20 or compound construction whereby the tenons on both ends of the rung or similar part of the chair may be made simultaneously.

Another purpose is to provide means whereby the cutters on the cutter head can 25 be adjusted for regulating the depth of the grooves or channels around the rungs, whereby the securement of the tenons in the cavities or bores of the legs or posts can be assured.

30 In constructing the tenons with the grooves by means of the particular arrangement of cutter heads, it is the aim to eliminate the use of glue or other fastening means when securing the tenons in the bores 35 or cavities of the posts or legs.

Still another purpose is to provide opposed correspondingly constructed cutter heads which support a rung between the ends 40 of the cutter head, and in the operation the cutter heads form the necessary grooves or channels in the tenons, the ends of the tenons being of such a size as to require the forcing or hammering of the tenons into the bores or cavities of the posts or legs of the 45 chair, thereby dispensing with glue or the like when a rung is connected to a post or leg.

Heretofore, all tenons on chair rung construction have been cut either on a hard 50 lathe or a back knife lathe which is very slow and uncertain in operation and this method has been found impractical to a certain degree.

A further purpose is to provide a double 55 or compound cutter head to facilitate the manufacture of what is known as old time

home-made chairs, dispensing with the hard or back knife lathe, saving expense in such manufacture, and to provide an improved cutter head which may be manufactured at 60 small expense and sold at a reasonable profit.

It is to be understood that the particulars herein given are in no way limitative and that, while still keeping within the scope of 65 the invention, any desired modifications of detail and desired proportions may be made in the apparatus according to the circumstances.

The invention comprises further features 70 and combinations of parts to be hereinafter set forth, shown in the drawings and claimed.

In the drawings:

Figure 1 is a view in side elevation of 75 an improved double or compound cutter head constructed in accordance with the invention.

Figure 2 is a longitudinal sectional view 80 through the same.

Figure 3 is a face view of one of the cutter heads, showing the means for grooving or channeling the surface of the tenon.

Figure 4 is a sectional view on line 4-4 85 of Figure 2.

Figure 5 is a detail view showing the cutter in elevation and the grooved tenon in section.

Referring to the drawings, 1 designates a spindle, it being understood that the spindles and the other construction of both cutter heads are the same in both instances. The spindle at one end is mounted in a bearing 2 and carries a pulley 3. Each spindle passes through the sleeve 4 on which a belt 90 95 pulley 5 is mounted. The pulley 3 is secured to the spindle by means of set-screws 6 so that the pulley will rotate with the spindle.

The belt pulley 5 is shiftable on the sleeve 100 by a ring 7 located in a space between a collar 8 and the shoulder 9 caused to be formed by the pulley 5. The pulley 5 has a frictional clutch face or depression 105 with which the frictional face of a clutch 10 member 11 engages, whereby when the pulley 5 is shifted so that the two clutch faces engage, the pulley and the clutch 11 rotate as one body.

A pair of belts for each cutter head are 110 employed. These belts respectively engage with the pulleys 3 and 5, while the belts are,

in turn, designed to engage an overhead single pulley (not shown). It will be noted that the pulley 5 is of less diameter than the pulley 3 and being that the two belts are operated through a unitary rotating member, the pulley 5 will rotate faster than the pulley 3, the purpose of which will hereinafter appear.

The sleeve 4 is operable in a bearing 12, 10 and secured to the sleeve by means of set-screws 12^a is a cutter head 13. One face of the cutter head is bored or recessed out, providing a cavity 14 for the reception of the auxiliary head 15 which is secured by 15 set-screws or the like 16 to one end of the spindle. The auxiliary head 15 operates in the main head 13. Mounted on one end of the spindle is a center 17 and also concentric with the center is a centering pin 18 20 with the projecting point of which the end of the chair rung engages to hold the chair rung concentric with the center of the cutter head.

Pivottally mounted upon the auxiliary head, as at 19, are oscillatory arms 20 which 25 carry cutters 21. The cutters are mounted and guided in recesses 22 of the arms and are disposed so that the cutting edges or cutting portions, as at 23, will form annular 30 grooves or recesses in the tenon of a chair rung. The cutters 21 are slotted and receive bolts 24 which permit the cutters 21 to be adjusted radially with relation to a chair rung to be engaged with the points of the 35 centering pins 18. By tightening the bolts 24 it is possible to hold the cutters in different positions, whereby their cutting edges may be adjusted to accommodate them to the surfaces of the tenons of the parts of a 40 chair.

The oscillatory arms lie against projections or pins 25 which are also carried by the auxiliary head. The pins or projections 25 are disposed so as to limit oscillatory movement of the arms in one direction and allow them to oscillate in the opposite direction. The pins or projections are 45 reversely disposed as shown. The outer extremities of the arms are forked, as shown 50 at 26, the forks engaging pins 27 which project from the flange of the head 13. A plate 28 is mounted upon the auxiliary head 15 and is provided with slots 29 which receive set screws 30 which are threaded into 55 the auxiliary head. The plate 28 has a projection 31 and is adapted to engage a projecting pin 32 carried by the flange of the head 13.

As previously stated, the pulley 5 is of 60 less diameter than the pulley 3 and since the pulley 5 is carried by the sleeve 4 and rotated through the medium of the clutch 11 and since the pulley 3 is carried by the spindle 1, the head 13 carried by sleeve 4 65 will rotate faster than the auxiliary head

15 carried by spindle 1, the two pulleys 3 and 5 being rotated from an overhead drive shaft. The head 13 rotates in the direction of the arrow shown in Figure 3, so does the head 15, but since the head 13 is much 70 faster in its revoluble movement, the pins will swing the arms 20 upon their pivots 19 and cause the projecting cutting edges or teeth of the cutters 21 to form or cut grooves or channels in the circumference of the 75 tenon formed on the end of a chair rung. By adjusting the plate 28, that is the distance between the projection 31 and pin 32, the depth of the cut made by the cutting ends or edges of the cutters 21 may be regulated. In other words, by adjusting the plate 28, the distance of movement of the arms 20 on their pivots 19 can be governed, thereby regulating the depth of the cutting 80 ends or edges of the cutters. 85

By forming grooves or channels in a tenon and thereby constructing large ends on the terminals of the tenons, after they have dried, and by driving the tenons into bores or cavities in the legs or posts of 90 chairs or the like which are still green, the bores or cavities being substantially smaller than the tenons, the walls of the bores or cavities will tighten around and hold the tenons secure without any glue or other fastening means to attain this result. By fastening tenons into bores or cavities of legs, 95 posts or other similar parts of a chair or other article, the tenon remains permanent 100 and never loosens.

Though one cutter head may be employed, there are disclosed opposed cutter heads mounted upon a bed 34 having guide channels 35 in which the frames 36 of both cutter heads are guided, and the bearings 2 and 105 12^a as well as the legs or supports of the rings 7 are carried by the movable frames 36, so that these parts of the frame move or are shifted in order to support a 110 chair rung and operate the clutch.

Secured to the remote ends of the bases 115 of both frames 36, as at 37, are springs 38, there being threaded studs 39 carried by the legs of the bearings 2 and projecting through the springs, so that by adjusting the nuts 40 on the studs, the tension of the springs 38 can be regulated. The springs also engage abutments 41 which are carried by the under parts of the bearings 2. The function of the abutments 41 is to limit the 120 pressure of the springs on the spindles to a certain position of the latter—that is, to relieve the spindles of spring pressure except when they are forced axially outward far enough to lift the springs from the abutments. The springs 38 engage reduced 125 ends of the spindles 1. Attached to the springs 38 are flexible members 42 which ride over pulleys 42' and have at their lower ends weights 44, the purpose being to return 130

the frames 36 to their initial positions in engagement with the remote end shoulders 45 of the guide channels 35, in which the ribs 36^a carried by the under faces of the bases 5 of the frames 36 are guided.

In order to groove the tenons of a chair rung, the rung 1^a may be placed in self-centering forks 46 which rise from the bed 34. When the chair rung is so placed, the frames 36 are in their normal positions engaging the remote shoulders 45 of the guide channels in order to permit the chair rung to be placed in position in the forks 46. After the rung is so placed, the foot of the operator engages with a pedal 47 pivoted upon a downward projection 48 of the bed 34. This pedal 47 is, in turn, connected by cables 49 passing over pulleys 50 which are carried by the bed 34, the cables being, in turn, connected at 51 to the adjacent ends of the bases of the frames 36. The pressure upon the pedal 47 causes the two frames 36 to move toward each other, and since the centering pins 18 are engaged with the ends of the rung (the spindles 1 moving slightly at first to permit the pins to so engage the rungs) the internal or auxiliary heads 15 move slightly with the spindles, but after the pins engage firmly with the ends of the rung, the spindles 1 do not move further. However, the pressure on the pedal 47 will impart movement to the frames 36 which causes the pulleys 5 to move until they engage frictionally with the clutch faces of the clutch members 11 and then, as previously stated, the external or main heads 13 move at a greater rate of speed than the internal or auxiliary heads, thereby operating the cutters.

After the tenons of the chair rung have been grooved, pressure may be relieved upon the pedal 47 so that, through the medium of the gravitation of the weights 44, the frames or carriages 36 are returned to their initial positions, that is, in engagement with the shoulders 45 of the guide channels. The return of the frames or carriages 36 to their initial positions will cause a disengagement of the clutch faces of the clutch member 11 and the pulley 5, and due to the spindles being still rotated through the medium of the pulleys 3, the arms 20 (which carry the cutters) are actuated to withdraw the cutting edges from engagement with the tenons of the chair rung.

This cutter head may be used double headed, as shown, or as a single head and in this latter case the frame 36 may be supported stationary and under such conditions the chair rung is held either in the hands or by a pair of pliers or by any other suitable means for the purpose of preventing rotation of the rung. However, the chair rung may be supported in a fork in front of the head, so as to center the chair rung

in position. The operator presses it up against the centering pin 18, whereby the tenon may be grooved. Also when using the machine employing a single head, a single frame 36 may operate in a guide of a bed, 70 still employing a foot pedal, such as shown in Figure 1, and in this case the chair rung may be supported in a fork and by applying pressure upon the pedal, the single frame 36 may be moved to cause the two clutch members 11 and 5 to engage for operating the cutters. It is obvious that a spring (not shown) may be employed in any conventional manner in lieu of the weights 44.

The invention having been set forth, what is claimed is:

1. A tenon grooving machine comprising opposed cutter heads, each consisting of main and auxiliary rotating heads, spindles on which the heads of both cutter heads are mounted and provided with means for the support of a chair rung, unitary means for rotating the two heads of each cutter head in the same direction, means for driving one head at a greater rate of speed than the other head, and channel or groove cutting means carried by one head and operatively connected with the other head for causing the groove or channel cutting means to engage and groove the tenons of a chair rung.

2. A tenon grooving machine comprising opposed cutter heads, each cutter head having main and auxiliary rotating heads, means for rotating the main head at a greater rate of speed than the auxiliary head, means for the support of a chair rung between the two cutter heads, and groove cutting means carried by the auxiliary head and having operative connection with the main head, whereby due to the increased rate of speed of the main head the groove cutting means engages with a tenon and cuts a groove therein.

3. A tenon grooving apparatus consisting of opposed cutter heads, each having main and auxiliary revoluble heads, means concentric with the heads for the support of a chair rung, means for rotating the main head faster than the auxiliary head, and channel or groove cutting members movably mounted on the auxiliary head and operatively connected with the main head, whereby due to the faster travel of the main head, pivotal motions are imparted to the members causing their cutting portions to engage with and groove the tenons of a chair rung.

4. A tenon grooving machine comprising means for the support of a chair rung, main and auxiliary revoluble heads, the former traveling faster than the latter, and tenon grooving members movably carried by the auxiliary head and operative by the main head for imparting movements to the groov-

ing members to cause them to engage and groove the tenons of a chair rung.

5. In a tenon grooving apparatus, the combination with a spindle having means for the support of a chair rung and carrying an auxiliary head, of a sleeve rotatable on the spindle and carrying a main head, the former being housed in the latter, means for rotating the spindle and the sleeve in 10 the same direction but at different speeds, whereby the main head may travel faster than the auxiliary head, and groove cutting members carried by the auxiliary head and in turn connected to the main head, whereby 15 the faster rotation of the latter will cause movement to be imparted to the members and hence cause their groove cutting ends to engage with and groove the tenons of a chair rung.

20 6. A tenon grooving machine comprising means for the support of a chair rung, main and auxiliary revoluble heads, the former traveling faster than the latter, tenon grooving members carried by the auxiliary head and operative by the main head for imparting movements to the members to cause cutting devices to engage and groove the tenons of a chair rung, and means for rotating the main and auxiliary heads in 25 the same direction, the construction and arrangement of said rotating means for the heads being such as to cause the main head to rotate faster than the auxiliary head.

30 7. In a tenon grooving apparatus, the combination with a spindle having means for the support of a chair rung and carrying an auxiliary head, of a sleeve rotatable on the spindle and carrying a main head, the former being housed in the latter, means for rotating the spindle and the sleeve in 35 the same direction but at different speeds,

whereby the main head may travel faster than the auxiliary head, groove cutting members carried by the auxiliary head and in turn connected to the main head, whereby 45 the faster rotation of the latter will cause movement to be imparted to the members and hence cause their groove cutting ends to engage with and groove the tenons of a chair rung, and means for limiting the 50 movement of the groove cutting members relative to the main head for regulating the depth of the groove to be cut in the tenon.

55 8. A tenon grooving machine comprising means for the support of a chair rung, opposing cutter heads with gravity means to hold them in their extreme remote normal positions, means for moving the cutter heads toward each other against the gravity 60 means to grip the chair rung, each cutter head comprising main and auxiliary revoluble heads, the former traveling faster than the latter, and tenon grooving members carried by the auxiliary head and operated 65 by the main head for imparting movement to the members to cause them to engage and groove the tenons of a chair rung.

70 9. In a tenon grooving machine, a bed, opposed cutter heads guided on the bed, gravity means for holding the cutter heads sufficiently spaced to permit the insertion of a chair rung, means for operating the cutter heads toward each other against the 75 gravity means to grip the chair rung, said cutter heads including tenon grooving means, and rotatable members carried by each cutter head operable at different speeds for actuating the tenon grooving means.

80 In testimony whereof he affixes his signature.

FRED J. MURDOCK.
